(57) CLAIM

The ornamental design for a stereo, as shown and described.

DESCRIPTION

FIG. 1 is a perspective view of a stereo;

FIG. 2 is a front view of the stereo of FIG. 1;

FIG. 3 is a rear view of the stereo of FIG. 1;

FIG. 4 is a left-side view of the stereo of FIG. 1;

FIG. 5 is a right-side view of the stereo of FIG. 1;

FIG. 6 is a top plan view of the stereo of FIG. 1;

FIG. 7 is a bottom plan view of the stereo of FIG. 1; and,

FIG. 8 is a front view of stereo of FIG. 1 in which evenly spaced broken lines illustrate an example environment of a stereo system.

The evenly spaced broken lines of FIG. 8 illustrating an environment form no part of the claimed design.
